UNITED STATES PATENT OFFICE

147,864

DESIGN FOR A PENCIL SHARPENER

Joseph Ness, Rockford, Ill., assignor to Rite-Rite
Mfg. Co., Downers Grove, Ill., a corporation of Illinois

Application March 3, 1947, Serial No. 137,286

Term of patent 14 years

(Cl. D74—1)

To all whom it may concern:

Be it known that I, Joseph Ness, a citizen of the United States, residing at Rockford, in the county of Winnebago and State of Illinois, have invented a new, original, and ornamental Design for a Pencil Sharpener, of which the following is a specification, reference being had to the accompanying drawings, forming part thereof.

In the drawings:

Fig. 1 is an elevational view showing one side of a pencil sharpener embodying my new design.

Fig. 2 is a similar view but showing the opposite side of the pencil sharpener shown in Fig. 1.

Fig. 3 is a top plan view.

Fig. 4 is a front elevation; and

Fig. 5 is a rear elevation.

I claim:

The ornamental design for a pencil sharpener, substantially as shown.

JOSEPH NESS.
